C. H. FOX.

WATER HEATER FOR AUTO FIRE ENGINES,
APPLICATION FILED SEPT. 23, 1918.

1,305,791.

Patented June 3, 1919.

Inventor:

Charles H. Fox.

By Wm. Wm.
Attorneys.

UNITED STATES PATENT OFFICE.

CHARLES H. FOX, OF CINCINNATI, OHIO.

WATER-HEATER FOR AUTO FIRE-ENGINES.

1,305,791.

Specification of Letters Patent. Patented June 3, 1919.

Application filed September 23, 1918. Serial No. 255,340.

To all whom it may concern:

Be it known that I, CHARLES H. Fox, a citizen of the United States, and residing at Cincinnati, in the county of Hamilton and 5 State of Ohio, have invented a new and useful Improvement in Water-Heaters for Auto Fire-Engines, of which the following specification is a full disclosure.

My invention relates to a water heater or 10 steam generator combined with the engine exhaust manifold of an automobile fire or pumping engine.

An object of the invention is to render 15 available a supply of steam or hot water with an auto fire or pumping engine in which the motive power is furnished by an internal combustion engine.

Another object of the invention is to provide a boiler having tubes or flues communicating with and intermediate of two exhaust lines, whereby all or a portion of the exhaust products from the engine may be conveyed through the boiler tubes for heating the water contained in the boiler.

25 Other objects and features, some relating to structural details, will definitely appear from the detailed description of the accompanying drawings, illustrating a preferred embodiment of the invention, forming a part of the specification, and in the drawings like characters of reference denote corresponding parts throughout the several views of which:

Figure 1 is a side elevation of my improved water heater and the upper portion of a plural cylinder internal combustion engine with which the heater is combined, showing the connection of the heater with the exhaust manifold of the engine for passage 35 of the exhaust products from the engine cylinder through flues or passages of the heater. A portion of the heater is shown in section to illustrate the heating flues.

Fig. 2 is an end elevation of the parts 40 shown in Fig. 1. Fig. 3 is a section on line 3, 3, Fig. 1, and

Fig. 4 is a plan view of the valve or shut-off plate located in a slide-way at the base of the heater for controlling the communication between the heater flues and engine exhaust manifold.

With the induction of automobile motor pumping engines as fire fighting apparatus, it has been found necessary to make provision for furnishing a supply of hot water or steam for emergency uses, principally

during the winter season, as for thawing frozen hose connections, fire plugs, and for scavenging various appliances and parts of the pumping apparatus to keep them in 60 an efficient working condition and prevent freezing.

Referring to the drawings, 1 indicates the several cylinders of an internal combustion engine, in this instance, six are illustrated, 65 although their number is optional.

An inlet manifold 2 connects with the upper ends of the cylinders, and an exhaust manifold 3 extending in a horizontal plane connects with the cylinders at one side thereof. The exhaust manifold 3 has its outlet end 4 extending downwardly in a vertical plane for the purpose of appropriately leading the exhaust pipe or main from the engine. As shown, the horizontal portion of 70 the exhaust manifold is formed of three sections, with the intermediate section 5 as a flanged T providing an elongated lateral opening 6 for establishing an upward course for the exhaust products passing through 75 the manifold. A horizontal tank or cylindrical bore 7, as a boiler, having flanged lower and upper faces is secured to and supported upon the coupling flange 8 of the intermediate T section 5 of the manifold 3, by bolts 80 passing through the coupling flange of the T section 5 into the base flange 9 of the boiler.

A series of tubes 10 extend crosswise or vertically through the boiler 7, having the 90 opposite ends fixed into the walls of the boiler in any well-known manner, to provide open end flues through the boiler communicating at their lower ends with the lateral opening 6 and exhaust manifold passage, 95 and at the upper ends with a conduit cap 11 secured upon and to the upper coupling flange 12 of the boiler. The conduit cap 11 is open at one end and connects with an end of a section of pipe 13 curved to lead downwardly and connecting with the flanged branch pipe fitting 14, likewise connecting with the depending manifold outlet end 4, bringing the two exhaust lines together to connect with a common discharge pipe, not 105 shown, but which connects with the branch fitting 14. The branch fitting 14 also serves as a casing for a butterfly valve 15, having its diametrical axis 16 extended through one side of the casing to which a crank arm 17 110 is fixed for swinging the valve. The opposite end of the crank arm connects with a

connecting rod 18 extending to an accessible point or reach of the operator.

- The boiler head 19, at its upper and lower sides, is provided with the integral nipple 5 extension 20, 20, to which the water lever gage 21 is connected. The water lever gage, at its lower body fitting has a drain-cock 22 connecting with a drain tube 23 for draining the water from the boiler. A suitable or 10 commercial type of safety valve may be provided for the boiler. 24 indicates a piping tapping into the upper portion of the boiler head 19, provided with a valve 25, which may serve alternately as a steam outlet or 15 water inlet, but this may be modified by providing separate outlet and inlet connections to meet the various demands of the men. The opposite boiler head 26 is provided with a pressure gage 27.
- 20 The base face of the boiler is recessed to provide a slide-way for the damper or exhaust controller plate 28, which slides between the boiler and intermediate manifold T section for shutting off or admitting the 25 exhaust gases from the engine into the boiler flues. The plate is provided with a series of apertures arranged and corresponding with the flues, so as to respectively register with the lower ends of the tubes. Moving the 30 plate 28 outwardly to bring the solid portions of the plate into line with the tube, shuts off communication with the tubes. The plate at its front end has a chain connected therewith as a handle for the operator. The plate is locked within its slideway, by a spring clip 30 fixed to the boiler side, having its free end projected to engage into 35 a notch 31 formed into the side edge of the damper or register plate.
- 40 In operation, the butterfly valve may be completely closed or regulated for blocking the outlet end of the exhaust manifold for directing the required amount of hot exhaust products from the engine through the 45 boiler flues, and thence through the sub-branch connecting with and leading from the upper end of the boiler, heating the water within the boiler around the tubes, to a degree sufficient to generate steam of a 50 volume sufficient to meet the demands required. It has been experienced that with this form of boiler, having vertical up-flues communicating with the exhaust manifold at a central point and in an upward course 55 direction, the flow of the exhaust products is not materially retarded nor is there any appreciable back pressure to any particular one of the cylinders of the engine. When the engine is operating under heavy duty 60 conditions, the controlling valve in the manifold can be set to admit a direct escape of a

proportion of the exhausting products as a relief, while a certain proportion is permitted to pass through the boiler flues.

Therefore, the heat for the boiler can be 65 exclusively regulated or controlled by adjustment of the butterfly valve in the manifold, and the plate valve of the boiler serve merely as an auxiliary for a more permanent control as for a complete opening or shutting of the flues. As there is practically no call for hot water or steam during the temperate seasons, it is desirable during such periods to have the heat cut off entirely from the boiler.

75

Having described my invention I claim:

1. The combination with an internal combustion engine, an exhaust manifold connecting with the respective cylinders of the engine, and a boiler comprising a horizontal 80 barrel, having a series of vertical tubes extended therethrough at one end in communication with said manifold, and a slideable valve plate for controlling the communication of all of said tubes with the said 85 manifold.

2. The combination with an internal combustion engine, an exhaust manifold extending in a horizontal plane connecting with the respective cylinders of the engine, 90 a boiler comprising a horizontal barrel mounted upon said manifold, having a series of vertical tubes extended therethrough communicating at the lower ends with said manifold, and a branch conduit connecting 95 with the boiler communicating with the opposite ends of said tubes and with said manifold.

3. The combination with an internal combustion engine, an exhaust manifold extending in a horizontal plane connecting with the respective cylinders of the engine, a boiler comprising a horizontal barrel mounted upon said manifold, having a series of vertical tubes extended therethrough communicating at the lower ends with said manifold, and a branch conduit connecting 100 with the boiler communicating with opposite ends of said tubes and with said manifold, and a valve in said manifold between its engine cylinder and branch conduit connections, regulatable for diverting all or a portion of the exhaust gases through said boiler tubes and branch conduit.

105 In witness whereof, I hereunto subscribe my name, as attested by the two subscribing witnesses.

CHARLES H. FOX.
